ERNST BORREGARD, OF GREAT NECK, NEW YORK, ASSIGNOR TO LEO H. FULLER, INC.,
OF LONG ISLAND CITY, NEW YORK, A CORPORATION OF NEW YORK

ADVERTISING DEVICE

Application filed February 7, 1930. Serial No. 426,518.

This invention relates to an advertising device adapted to be placed upon the article to be sold or upon the container within which the article is usually packaged for merchandising.

It is an object of this invention to produce such a device which will be colorful, attractive to the eye, and serve the utilitarian purpose of particularly designating or attracting the observer's attention to a definite part of the article or package, usually to the name or title of the article.

Another object is to produce a figure, human, animal or inanimate, but preferably a human figure of pleasing, colorful and also striking appearance, which will not only catch and hold the observer's eye because of these characteristics but which also possesses the characteristic of arrested animation.

This result is obtained by giving the device a configuration and a relationship to the article advertised, so that it appears that the figure embodied in the advertising device is clinging on to the edge of, or, perhaps, attempting to climb over the top of, the object or package to which the device is attached.

A still further object is to produce a device which may be attached to objects of various thicknesses and of any configuration, so that it will have a wide range of adaptability in the merchandising field, and is not limited to any particular class or size of goods.

Fig. 1 illustrates a front elevation of the advertising device applied to a phonograph record.

Fig. 2 is a partial side elevation of the device and record illustrated in Fig. 1.

Fig. 3 is a rear elevation of that which is shown in Fig. 1.

Fig. 4 is a front elevation of a similar device embodying a different figure.

Fig. 5 is a front elevation of an advertising device adapted to be used on a package having a considerable thickness, and illustrates still another type of figure which may be used.

Fig. 6 is a partial plan view of what is shown in Fig. 5.

Fig. 7 is a partial side elevation of that which is shown in Fig. 5.

In Figs. 1, 2 and 3, I have illustrated a preferred embodiment of my invention adapted to be used in combination with an article possessing very little thickness, such as a phonograph record. R represents the usual disc-like phonograph record supported upon a pedestal P for the purpose of holding it substantially vertical, so that when it is placed in a show case or show window, printed matter thereon may be readily noted by the passer-by.

The advertising device itself comprises a figure F adapted to simulate a boy dressed in the attire of a cowboy and comprising a body portion with a leg 1 and a left arm 2 and a right arm 3 attached thereto. An animal, inanimate or purely fanciful figure may be used. The figure is so cut and shaped relative to the edge of the disc that it may be placed thereon, and the leg and both arm portions will extend over and rest upon the outer face of the disc, as illustrated, whereby the body portion will be positioned above the disc with the result that the general appearance is such as would be given by a figure attempting to cling on to or climb over the top of the record. The device is attached to the edge of the record in this manner, with the aid of an engaging arm 5 attached to the back of the device parallel thereto and spaced therefrom by a spacing block 6.

In this particular embodiment of my invention, the block 6 is of the same thickness as the record so that the edge of the record will readily slip between the outer face of the figure F and the engaging arm 5, and thus, with the co-operation of the leg and the arm members, the advertising device may be secured to the edge of the record. As will be noted by inspection of Fig. 1, left arm 2 is adapted to direct the observer's attention to the printed matter upon the circular blank space adjacent to the center of the record. In this manner, the advertising device, not only attracts the attention of the casual observer because of its pleasing, colorful and novel appearance, but it also serves to focus his attention upon the particular portion of the device to be emphasized.

The device is illustrated as combined with

a phonograph record but it is contemplated to use it in conjunction with ordinary display cards or with other articles of manufacture possessing little relative thickness.

5 Fig. 4 illustrates another figure which may be utilized to advertise a phonograph record. This figure is adapted to simulate a pirate and it comprises the usual body portion F, the leg portion 1, and the left arm portion 2 10 and the right arm portion 3, and also the engaging arm 5.

In Fig. 5, I have illustrated a device adapted to be attached to a package instead of to a thin disc. At 10, is illustrated a package 15 of common proportion and dimension which might be used for packaging many articles of manufacture, and which presents a rectangular elevation on all sides thereof. The figure comprises a body portion F', a leg portion 11, a left arm portion 12 and a right arm portion 13, in general, similar to and possessing the same relationship to each other as the elements F and 1, 2 and 3 described in regard to Figs. 1 to 4 inclusive. The leg portion 11 and the two arm portions 12 and 13 are adapted to overlap the front of the box, while the body portion F' rests upon the edge of the top and side as illustrated in Fig. 5.

30 The particular figure illustrated in Fig. 5 is adapted to simulate a clown, and when positioned as shown, gives the appearance of a figure clinging to or attempting to climb over the package of goods and arm 12 serves to point out or designate the name printed 35 upon the outside of the package.

The structure of the means adapted to hold the figure in place upon the box comprises a U-shaped horizontal member 15, one vertical arm of which, 16, is adapted to be secured 40 to the back of the figure F', and the other vertical arm 17 is adapted to be secured to the elongated vertically disposed engaging arm 18. The horizontally disposed portion of the U-shaped portion 15 is adapted to rest upon 45 the top of the package, while the figure F' and the vertically disposed engaging arm 18 engage the front and rear of the package respectively, and in this manner, the advertising device may be securely, though detachably, positioned upon an ordinary package or 50 carton. The horizontally disposed portion of the U-shaped device 15 possesses a pair of upturned right angularly disposed reinforcing ears 19 and 20 which may be punched out 55 of the horizontally disposed portion, and folded up therefrom at an angle of 90° thereto, in such a position as to reinforce the vertically disposed arms 16 and 17 and serve 60 to maintain them at substantially right angles to the horizontally disposed portion 15.

This display device is adapted to be made of cardboard, strawboard, or similar material, which is of low cost, yet readily adapted 65 to receive coloring and printing.

Whereas I have described my invention by reference to specific forms thereof, it will be understood that many changes and modifications may be made without departing from the spirit of the invention.

70

I claim:

1. In a device of the character described, a figure of such color and configuration as to simulate a human figure in the act of clinging to the edge of the article or package to be advertised, and with a portion thereof extended to point out and attract attention to a particular part of said article or package, and means for attaching said figure to said article or package in proper relationship thereto, comprising a spacing member of U-shaped configuration, and an attaching arm secured to said spacing member in co-operative relationship with said figure to secure said device to the article or package to be 85 advertised.

80

2. In a device of the character described, a figure of such color and configuration as to simulate an animate figure in the act of clinging to the edge of the article or package to be advertised, and of such appearance as to arrest and hold an observer's attention, and adapted to co-operate with an edge portion of the article or package to be advertised, and with a portion thereof extended to point 95 out and emphasize a particular part of said article or package, and means for attaching said figure to said article or package in proper relationship comprising a member secured to the rear of said figure and of such small size 100 in comparison with the figure as to be concealed from the observer when viewing the device from the front and extending to a side of the article or package opposite to said extending portion of the figure.

105

In testimony whereof I have signed this specification this 31st day of January, 1930.

ERNST BORREGARD.
